(57) **CLAIM**

The ornamental design for a folder, as shown and described.

DESCRIPTION

FIG. 1 is a front, left and top perspective view of a folder, showing my new design;

FIG. 2 is a rear, right and bottom perspective view thereof;

FIG. 3 is a front elevation view thereof;

FIG. 4 is a rear elevation view thereof;

FIG. 5 is a left side elevation view thereof;

FIG. 6 is a right side elevation view thereof;

FIG. 7 is a top plan view thereof;

FIG. 8 is a bottom plan view thereof;

FIG. 9 is another perspective view of the folder, shown in an alternate configuration;

FIG. 10 is another perspective view of the folder, shown in an alternate configuration;

FIG. 11 is an enlarged view of the portion labeled with the number **11** in FIG. 1;

FIG. 12 is an enlarged view of the portion labeled with the number **12** in FIG. 5;

FIG. 13 is an enlarged view of the portion labeled with the number **13** in FIG. 7;

FIG. 14 is an enlarged view of the portion labeled with the number **14** in FIG. 1;

FIG. 15 is an enlarged view of the portion labeled with the number **15** in FIG. 2; and,

FIG. 16 is an enlarged view of the portion labeled with the number **16** in FIG. 7.

The dash-dash broken lines in the drawings depict portions of the folder that form no part of the claimed design. The dash-dot-dash broken lines shown in FIGS. 1, 5, 7, 11, 12, 13, 14, 15 and 16 are for the purpose of depicting the boundary line of the enlarged view and form no part of the claimed design.

1 Claim, 16 Drawing Sheets
